STORAGE UNIT FOR AN AIRCRAFT GALLEY OR THE LIKE

Anthony J. Fiori, Seac Cliff, Edward J. Dziedziula, North Massapequa, and Ralph R. Pecoraro, West Islip, N.Y., assignors to Ref Manufacturing Corporation, Mineola, N.Y., a corporation of New York

Filed Jan. 8, 1959, Ser. No. 54,077

Term of patent 14 years

(Cl. D81—10)

Fig. 1 is a perspective view showing the front and one side of a storage unit for an aircraft galley, the rear and opposite side thereof being substantially plain;

Fig. 2 is a side elevation of Fig. 1 taken from said one side thereof; and

Fig. 3 is a top view of Fig. 1.

We claim:

The ornamental design for a storage unit for an aircraft galley or the like, substantially as shown and described.
